ABSTRACT

In a flint lighter of the disposable type the rotary knurled wheel has a central bore by which it is mounted on a spindle or elongated boss between a pair of deformable plastic holdfasts. One end of the boss is formed integrally with one holdfast and the other end is ball shaped and inserted into an opening in the other holdfast after the knurled wheel is placed on the boss. Alternatively, the holdfasts can each be provided with a facing boss, each located in an opposite end of the bore, or the wheel may have a central boss projecting from each side and located in openings in the holdfasts.

FIG.1

FIG.2

FIG.3

FIG.4

FLINT LIGHTERS WITH A ROTARY KNULED WHEEL

This invention relates to improvements in flint lighters with a rotary knurled wheel.

In known flint lighters with a rotary knurled wheel, the knurled wheel is generally mounted on a pin which is either free or integral with the knurled wheel or lighter.

A common drawback of these arrangements is the presence of an added pin which must be formed and possibly machined, then be subjected to various operations before being mounted on the lighter.

An object of the present invention is to simplify and remove these operations, while facilitating the mounting of the knurled wheel on lighters of the so-called "disposable" type, the flint spring and flint of which are disposed in a recessed pipe before the knurled wheel is positioned.

According to the invention a flint lighter with a rotary knurled wheel comprises said knurled wheel being supported by at least one boss.

According to another feature of the invention, the free end of the boss is itself secured to the body of the lighter.

According to another feature of the invention, the knurled wheel is supported by two axial bosses disposed on the body of the lighter and resiliently interconnected in a direct or indirect manner.

Further features of the invention will be apparent from the ensuing description of several embodiments, with reference to the drawing given by way of example in a purely indicative and non-limiting manner. In the drawing:

FIG. 1 is an end view partly in section of one embodiment of lighter formed according to the invention,

FIG. 2 is a view on II-II in FIG. 1, and

FIGS. 3 and 4 are fragmentary side elevations partly in section of two further embodiments of the invention.

In FIGS. 1 and 2, a body 1 of a partially outlined lighter supports a head 2 constituted by a more or less flexible moulded piece of plastic material which comprises a central rounded portion 3 and two plane end holdfasts 4 and 5.

The moulded flanges or holdfast 4 comprises an elongated boss 6 which ends in a small ball 7 whereas the holdfast 5 is provided with a perforation 8.

Additionally, the holdfast 4 is provided with a catch 9 and the holdfast 5 with a catch 10.

Finally the body 1 comprises at its upper part, two or engagement portions 11 and 12 each of which is provided with a groove 13 and 14.

In these conditions, the mounting is carried out as follows: when a knurled wheel 15 has been disposed on the boss 6 of the holdfast 4, the small ball 7 at the free end of this boss is inserted in the perforation 8 of the holdfast 5 to join the boss thereto, and the head 2 is placed on the body 1 so that the catches 9 and 10 of the head face the bosses 11 and 12 of the body. The head then bears against the body; the catches 9 and 10 are inserted until they engage in the grooves 13 and 14 where they are locked owing to their particular shape.

Taking into account the dimensions of a pocket lighter,

this locking is sufficient to hold the head on the body. However, it is evident that if it is desired to make a lighter of greater dimensions, another locking on the same principle must be provided.

5 In FIG. 3, instead of arranging the knurled wheel 15 on a single elongated boss, two axial bosses 16 and 17 are provided, disposed in opposition on two holdfasts 18 and 19 moulded with the body 1.

10 In FIG. 4, it is the knurled wheel 20 which supports two bosses 21 and 22 which are journalled in two housings 23 and 24 of two holdfasts 25 and 26.

Naturally, modifications of construction details or their arrangement may be made with a view to obtaining the same result without diverging from the spirit of 15 the invention.

For example, the constructions shown in FIGS. 3 and 4 could be combined by using a knurled wheel with a boss on one side and a housing on the other side, the boss, in the housing, taking the place of the head of the 20 lighter, and the housing provided in the knurled wheel receiving a boss moulded with the head of the lighter.

One advantage of the arrangement is that the asymmetry of the knurled wheel makes it possible to position it with an automatic sorter even when its ribs are 25 orientated.

What is claimed is:

1. A flint lighter comprising:
a body,
a moulded head independent of the body,
a knurled wheel,
said head including opposed flanges and being sufficiently elastic to enable the flanges to be separated to allow the wheel to be inserted between said flanges,
boss means coupling said wheel and said flanges to enable the wheel to rotate,
said head, boss means and wheel forming a sub-assembly,
engagement portions on said body,
and groove and catch means for connecting said sub-assembly with said engagement portions by a snap-engagement and providing sufficient necessary rigidity for operation of the wheel.

45 2. A lighter as claimed in claim 1 wherein said head flanges support said boss means.

3. A lighter as claimed in claim 2 wherein the boss means is integral with one flange and engageable in the other.

50 4. A lighter as claimed in claim 1 wherein said groove and catch means comprises catch members on said flanges so positioned to lockably engage said engagement portions to hold the sub-assembly on the body in substantially rigid engagement.

55 5. A lighter as claimed in claim 4 wherein said engagement portions have grooves and said catch members are positioned to resiliently snap-engage into said grooves when said flanges are inserted between the engagement portions.

60 6. A lighter as claimed in claim 1 wherein said head includes a loop portion integral with said flanges.

7. A lighter as claimed in claim 1 wherein said boss means comprises a boss on each flange rotatably received in a bore provided in said wheel.
